Nelson W. Ronald

UNITED STATES PATENT OFFICE.

ALBERT J. HORNE, OF PARK RIDGE, ILLINOIS, ASSIGNOR TO UNITED SHOE MANUFACTURING CORPORATION, OF PATERSON, NEW JERSEY, A CORPORATION OF NEW JERSEY.

FASTENER-INSERTING MACHINE.

Application filed November 9, 1925. Serial No. 67,893.

This invention relates to the insertion of fasteners and is illustrated herein as embodied in a machine particularly adapted to insert blind or invisible eyelets.

5 In the manufacture of boots and shoes blind and invisible eyelets are commonly inserted by a machine provided with a setting tool having a small clenching shoulder arranged to be introduced from one side of 10 the work through a lacing hole so as to meet and clench the entering end of the eyelet barrel between adjacent layers of the work. In operating machines of this character, difficulties at times are met with in 15 forcing the layer of the work beneath which the eyelets are to be clenched past the clenching shoulder of the setting tool. If this layer of the work (the upper leather in the case of invisible eyeleting) does not pass the 20 clenching shoulder by the time the entering end of the eyelet barrel reaches the clenching shoulder, the prongs of the eyelet are likely either to pass upwardly into the lacing hole so that they are visible in the finished work or to enter the substance of the 25 upper leather as they spread, thus enlarging the lacing hole.

It is accordingly an object of the present invention to overcome this difficulty by providing an improved fastener-inserting machine organization arranged to ensure that the layer of the work beneath which the fasteners are to be clenched is forced past the clenching surface of the setting tool before the insertion of each fastener. Thus the illustrated machine is provided with novel means arranged to engage the work substantially at the edge of the lacing hole upon the side opposite that from which the setting tool is introduced and to force the layer beneath which the fasteners are to be clenched past the clenching shoulder of the setting tool. Preferably, and as illustrated herein, this means for forcing a layer of the 40 work past the clenching shoulder of the setting tool comprises a plurality of fingers surrounding the fastener-inserting tool or "bottom set" of the machine and arranged, after they have forced a layer of the work past the clenching shoulder of the setting tool, to be moved radially away from the lacing hole so as to permit the insertion and clenching of the fastener.

With the above and other objects and features in view, the invention will now be de-

scribed in connection with the accompanying drawings and pointed out in the claims.

In the drawings,

Fig. 1 is a perspective view of an eyelet-inserting machine embodying the present invention; 60

Fig. 2 is a perspective view of the means for forcing a layer of the work past the clenching shoulder of the setting tool;

Figs. 3, 4, 5 and 6 are sectional views of 65 the mechanism of Fig. 2, illustrating different positions which the parts assume during the operation of the machine;

Figs. 7 and 8 are sectional views illustrating a novel arrangement for mounting the 70 setting tool in the tool holder of the machine.

The invention is illustrated herein as embodied in an eyelet-inserting machine of the type disclosed in United States Letters Patent No. 1,205,277, granted Nov. 21, 1916, on an application of Walter Shaw, to which reference may be had for a more detailed description of the machine than is included herein. 75

The illustrated machine is provided with a main cam shaft 12 from which the various parts of the machine are operated. These parts include a lever 14 arranged to carry an eyelet-setting tool 16 provided with a clenching shoulder 18. As illustrated this setting tool is a combined punch and set and is operative to punch the holes in which the eyelets are to be inserted as well as to feed the work from punching to eyelet-inserting position. With these purposes in view, the machine is provided with a punch block 20 and with a presser foot 22 moved out of engagement with the work during the feeding movement of the setting tool 16 and clamping the work against the work table 24 of the machine during the return movement of the setting tool after an eyelet has been set. The machine is also provided with an eyelet-inserting tool or 100 "bottom set" 26 bored to receive a spindle 28 arranged for reciprocating movement to take eyelets one at a time from a raceway 30 and hold them in alignment with the setting tool as they are introduced into the 105 holes punched in the work.

In order to ensure that the layer of the work beneath which the eyelets are to be clenched (the upper leather in the case of invisible eyeleting) is past the clenching 110

shoulder of the setting tool before the prongs of the eyelet are spread during the clenching operation, the illustrated machine is provided with a plurality of resilient fingers 32 surrounding the eyelet-inserting tool 26 and provided with flat end portions 34 substantially surrounding the spindle 28, the fingers 32 being bent inwardly at the top and arranged to be brought into engagement with the work after it has been fed to eyelet-inserting position but before the insertion of the eyelet so as to engage the work over an area extending to the edge of the lacing hole on the side of the work opposite to that from which the setting tool is introduced, endwise movement of fingers 32 then forcing the upper layer of the work past the clenching shoulder 18 of the setting tool. Fingers 32 are carried by a ring 38 mounted for sliding movement on the eyelet-inserting tool 26 and supported by a spring 40 bearing at its lower end upon a collar 42 secured to the inserting tool 26. Endwise movement of fingers 32 relatively to the inserting tool 26 is limited by a pin-and-slot connection 43, the slot, however, being of sufficient width to permit a certain amount of rotary movement of fingers 32 and ring 38 upon the inserting tool 26. The inserting tool 26 is provided near its upper end with a cam 44 illustrated as having three elevated portions arranged to engage the inner surfaces of the three fingers 32 and, when rotary movement is imparted to fingers 32, to force them outwardly radially of the lacing hole so as to permit the passage of an eyelet between fingers 32 as it is introduced into the lacing hole. For this purpose the ring 38 is provided with a ball 46 located in a socket 48 formed in a two-part block 48 arranged for sliding movement in a slot 50 formed in the upwardly extending arm of a bell crank lever 52 pivoted at 54 to the frame of the machine. The other arm of the bell crank lever 52 is provided with a cam roll 56 located in a suitably formed cam groove 58 formed in a cam member 60 carried by shaft 12.

In the operation of the machine, after the work has been punched by the setting tool and fed to eyelet-inserting position, the eyelet-inserting tool 26 with its spindle 28 is moved upwardly to pick an eyelet from the end of the raceway 30 which is then withdrawn. At this time fingers 32 are held by cam 44 away from spindle 28, as shown in Fig. 3, so that the eyelet may drop down and rest upon a seat 62 formed at the upper end of the eyelet-inserting tool 26. Then as cam 60 rotates, bell crank lever 52 is rocked so as to bring fingers 32 opposite to the low portions of cam 44, whereupon the upper ends 34 of these fingers spring inwardly, as shown in Fig. 4. As the inserting tool 26 moves upwardly, fingers 32 engage the work

at the edge of the lacing hole and force the work lengthwise of the setting tool until the layer beneath which the eyelets are to be clenched, illustrated at 64, is forced past the clenching shoulder 18 of the setting tool and into engagement with an abutment 65 carried thereby, as shown in Fig. 5. Bell crank lever 52 is then rocked to bring fingers 32 opposite the raised portion of cam 44. Fingers 32 are thus moved outwardly, and as the inserting tool 26 continues its upward movement, spring 40 is compressed, as shown in Fig. 6. The eyelet is thus enabled to pass upwardly between the upper ends of fingers 32 and its barrel passes through the lower layers (such as the facing 66 and eyelet stay 68) and is clenched by the clenching shoulder 18 between the layers of the work. Thereafter the eyelet-inserting tool 26 is lowered, the work being held against movement by presser foot 22, and the setting tool 16 is withdrawn and returned to punching position.

In the illustrated machine the eyelet-setting tool 16 is formed with a shank tapered for reception by a diverging opening 70 formed in a tool holder 72 carried by lever 14. The tapered shank of the setting tool may extend clear to the clenching shoulder 18, as at 74 in Fig. 8, or a cylindrical portion 76 may be interposed between the clenching shoulder and the tapered shank, as illustrated in Fig. 7, as may be desired.

Having described the invention, what I claim as new and desire to secure by Letters Patent of the United States is:

1. A machine for inserting barreled fasteners in a work-piece comprising a plurality of layers of material and clenching the entering ends of their barrels between adjacent layers of the material having, in combination, a combined punching and setting tool provided with a clenching shoulder formed and arranged to be introduced from one side of the work through a hole punched by said tool, and means arranged to engage the work on the other side substantially at the edge of the hole while the work is at fastener-inserting position arranged by movement toward said tool to force a layer of the material past the clenching shoulder of the tool.

2. A machine for inserting barreled fasteners in a work piece comprising a plurality of layers of material and clenching the entering ends of their barrels between adjacent layers of the material having, in combination, a combined punching and setting tool provided with a clenching shoulder formed and arranged to be introduced from one side of the work through a hole punched by said tool, and means arranged to engage the work upon the other side substantially at the edge of the hole while the work is at fastener-inserting position but before the

introduction of the fastener and arranged by movement toward said tool to force a layer of the material past the clenching shoulder of the tool.

5. A machine for inserting eyelets in a work-piece comprising a plurality of layers of material and clenching the entering ends of their barrels between adjacent layers of the material having, in combination, a combined punching and setting tool provided with an eyelet-clenching shoulder, means for operating said tool to cause it to punch a hole in the work and to feed the work to eyelet-inserting position, and means operating after the work has been fed to eyelet-inserting position to engage the work substantially at the edge of the hole and movable toward the tool to force a layer of the work past the clenching shoulder of the tool 20 before the introduction of an eyelet in the hole.

4. A machine for inserting barreled fasteners in a work-piece comprising a plurality of layers of material and clenching the entering ends of their barrels between adjacent layers of the material having a fastener-setting tool arranged to feed the work to fastener-inserting position, and means operative after the work has been fed to fastener-inserting position to engage the work substantially at the edge of the hole in which a fastener is to be inserted and by relative movement of said means and the setting tool to force a layer of the material past the clenching shoulder of the tool.

5. A machine for inserting eyelets in a work-piece comprising a plurality of layers of material and clenching the entering ends of their barrels between adjacent layers of the material having a setting tool provided with a clenching shoulder arranged to be introduced from one side through a lacing hole to clench the entering end of an eyelet barrel between adjacent layers of the work, means arranged to engage the work at the other side operative to force a layer of the work past the clenching shoulder of the tool, and mechanism for withdrawing said means radially of the hole after said layer has been forced past the clenching shoulder to permit the insertion of an eyelet in the hole.

6. A machine for inserting eyelets in a work-piece comprising a plurality of layers of material and clenching the entering ends of their barrels between adjacent layers of the material having a setting tool provided with a clenching shoulder arranged to be introduced from one side through a lacing hole to clench the entering end of an eyelet barrel between adjacent layers of the work, means arranged to engage the work at the other side movable toward the setting tool to force a layer of the work past the clenching shoulder of the tool, and cam mechanism arranged to move said means radially away

from the hole to permit the subsequent insertion of an eyelet in the hole.

7. A machine for inserting eyelets in a work-piece comprising a plurality of layers of material and clenching the entering ends of their barrels between adjacent layers of the material having a setting tool provided with a clenching shoulder arranged to be introduced between adjacent layers of the work from one side through a lacing hole, and a plurality of fingers arranged to engage the other side of the work substantially at the edge of the hole and movable toward the setting tool to force a layer of the work past the clenching shoulder of said tool.

8. A machine for inserting barreled fasteners in a work-piece comprising a plurality of layers of material and clenching the entering ends of their barrels between adjacent layers of the material having a setting tool provided with a clenching shoulder arranged to be introduced between adjacent layers of the work from one side through a hole, a plurality of fingers arranged to engage the other side of the work substantially at the edge of the hole and movable toward the setting tool to force a layer of the work past the clenching shoulder of said tool, and means for moving said fingers away from the hole after said layer has been forced past the clenching shoulder.

9. A machine for inserting eyelets in a work-piece comprising a plurality of layers of material and clenching the entering ends of their barrels between adjacent layers of the material having, in combination, an eyelet-setting tool provided with a clenching shoulder arranged to be introduced from one side through a lacing hole to clench the entering end of an eyelet barrel between adjacent layers of the work, and means arranged to engage the other side of the work to force a layer of the work past said clenching shoulder, said means comprising a plurality of fingers arranged to engage the work over an area extending substantially to the edge of the lacing hole, means for moving said fingers in the direction of the setting tool while thus positioned to force a layer of the work past the clenching shoulder of the tool, and cam mechanism arranged thereafter to move said fingers radially away from the hole to permit the insertion of an eyelet in the hole.

10. A machine for inserting eyelets in a work-piece comprising a plurality of layers of material and clenching the entering ends of their barrels between adjacent layers of the material having, in combination, an eyelet-setting tool provided with a clenching shoulder arranged to be introduced from one side through a lacing hole to clench the entering end of an eyelet barrel between adjacent layers of the work, an eyelet-inserting tool, a plurality of fingers surrounding the

inserting tool and arranged to engage the work over an area extending substantially to the edge of the lacing hole, means for moving said fingers in the direction of the setting tool while thus positioned to force a layer of the work past the clenching shoulder of the tool, and a cam arranged there-

after to move said fingers radially of the hole to permit the inserting tool to introduce an eyelet into the hole. 10

In testimony whereof I have signed my name to this specification.

ALBERT J. HORNE.
